UNITED STATES PATENT OFFICE.

MILTON DORN, OF TELFORD, PENNSYLVANIA.

COMBINATION UTENSIL.

1,143,084.

Specification of Letters Patent. Patented July 27, 1915.

Application filed June 2, 1914. Serial No. 342,758.

To all whom it may concern:

Be it known that I, MILTON DORN, a citizen of the United States, residing at Telford, in the county of Montgomery and State of Pennsylvania, have invented new and useful Improvements in Combination Utensils, of which the following is a specification.

The invention relates to a combination utensil.

The primary object of the invention is the provision of a combination device wherein the same can be converted into a cup, funnel, strainer, or used with a lamp or stove, thus making it handy and useful in a sick room or as a household commodity.

Another object of the invention is the provision of a device of this character which is readily and easily assembled or disassembled to enable the convenient use thereof for the purposes intended therefor.

A further object of the invention is the provision of a device of this character which is simple in construction, reliable and efficient in its use, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing, Figure 1 is a vertical sectional view through the device constructed in accordance with the invention. Fig. 2 is a plan view looking toward one end of the funnel, with the strainer therein. Fig. 3 is a perspective view of the strainer removed. Fig. 4 is a perspective view of the removable cap for the cup.

Similar reference characters indicate corresponding parts throughout the several views in the drawing.

Referring to the drawing in detail, 5 designates a cylindrical cup, preferably made from metal, having the usual handle 6 mounted exteriorly on the side thereof, while 7 indicates a funnel which is also preferably made from metal and is formed in its larger end with an annular groove 8 with which engages a split ring 9 which is detachably held within the larger end of the funnel for supporting a strainer hereinafter described.

The strainer comprises a frusto-conical shaped body 10 having at its smaller end a

reticulated strainer disk 11 which is secured thereto in any suitable manner, and this body 10 is adapted to be removably fitted within the larger end of the funnel 7 and held therein by the ring 9 which carries tie wires 12 to prevent undue spreading of the ring and also to reinforce the same. On the placing of the strainer body 10 within the funnel 7 the smaller end of the funnel can be inserted in a receptacle or bottle for the filling of the same with liquid, and as the latter flows through the funnel it will pass through the strainer disk 11 for removing any foreign matter therefrom. If desired a strainer fabric can be placed over the larger end of the funnel 7 and the ring 9 will firmly clamp the fabric in place so that it may be used as a fine strainer.

Detachably engaged in the smaller end of the funnel 7 is a spring clip 13 which is mounted centrally upon the disk-like cap 14 which is adapted to close the smaller end thereof when the funnel is inverted and placed within the latter so that the cup may be placed upon a stove or over a lamp chimney for the heating of the contents thereof. The cap is readily removable from the funnel so that it may be used in the ordinary well-known manner for the filling of bottles or receptacles, or on the placing of the strainer therein the liquid poured into the funnel can be strained for removing foreign matter therefrom. The larger end of the funnel 7 is fixed to the wall of the opening centrally in the bottom of the cup 5, as shown in Fig. 1 of the drawing. The tie wires 12 carried by the ring 9 serve to prevent the funnel from going down over the chimney of a lamp too far when heating the contents of the cup 5, as will be clearly apparent.

What is claimed is:—

1. The combination with a cup having an opening in its bottom, of a funnel fixed at its larger end to the wall of the opening in the bottom of the cup, a truncated cone removably fitted within the larger end of the funnel, and a strainer mounted in the smaller end of the cone.

2. The combination with a cup having an opening in its bottom, of a funnel fixed at its larger end to the wall of the opening in the bottom of the cup, a truncated cone removably fitted within the larger end of the funnel, a strainer mounted in the smaller end of the cone, the said funnel spaced from

its larger end being formed with an internal annular groove, a resilient split ring engaged in the groove for detachably holding the cone in the larger end of the funnel, and 5 cross wires carried by the ring.

3. The combination with a cup having an opening in its bottom, of a funnel fixed at its larger end to the wall of the opening in the bottom of the cup, a truncated cone 10 movably fitted within the larger end of the funnel, a strainer mounted in the smaller end of the cone, the said funnel spaced from its larger end being formed with an internal

annular groove, a resilient split ring engaged in the groove for detachably holding the 15 cone in the larger end of the funnel, cross wires carried by the ring, and a cap having spring fingers detachably engaged in the smaller end of the funnel for closing the said end.

In testimony whereof I affix my signature in presence of two witnesses.

MILTON DORN.
